UNITED STATES PATENT OFFICE

ANDREW CHRISTIANSON, OF PITTSBURGH, PENNSYLVANIA

COUPLING MECHANISM

Application filed July 27, 1927. Serial No. 208,715.

This invention relates to railroad cars and more particularly to improvements in the coupling and draft mechanisms of such cars.

In coupling railroad cars it is necessary to bring them together with sufficient force to insure obtaining an operative engagement between the respective couplers. This results in the car buffers being brought together with a severe and undesirable jar, a large part of which is transmitted through the buffer springs to the cars themselves.

An object of this invention is to provide a mechanism of the type set forth constructed and arranged to permit the coupling together and operation of railroad cars without undue jarring.

A further object is to provide a mechanism for the purpose specified which will be simple and rugged in construction and durable and effective in operation.

These and other objects which will be readily apparent to those skilled in this particular art are accomplished by means of the invention illustrated in the accompanying drawings, in which Figure 1 is a longitudinal sectional view through a coupling and draft mechanism constructed in accordance with one embodiment of this invention, and illustrating the coupler in advanced coupling position. Fig. 2 is a partial sectional view on the line 2-2 of Fig. 1. Fig. 3 is a transverse sectional view on the line 3-3 of Fig. 1. Figs. 4 and 5 are similar views on the lines 4-4 and 5-5, respectively, of Fig. 1; and Fig. 6 is a view similar to Fig. 1, but illustrating the coupler in retracted operating position.

In the usual construction of railroad cars the relative positions of the buffers and couplers are such that the former receives a jolt severe enough to compress the buffer springs in bringing the couplers of the respective cars into coupling engagement, and the resulting jar is, at least partially, transmitted to the car body. The present invention contemplates the provision of a mechanism which is so constructed and arranged as to eliminate the necessity of any sudden and severe contact between the buffers of railroad cars in order to accomplish the coupling operation.

In the illustrated embodiment of this invention, this is accomplished by providing a coupling mechanism having a coupler which can be shifted out of its normal, retracted operating position into a position somewhat in advance of the car buffer for coupling purposes. When in advanced, coupling position the car couplers can be connected together without jarring or forcibly engaging the car buffers, and the construction is such that after the coupling operation, the couplers will be automatically retracted to their normal operating or driving position.

The particular embodiment of the present invention which has been chosen for the purposes of illustration includes a coupler 10, of any standard form, having a shank 11 slidably mounted for longitudinal movement in a housing 12 and normally pressed forwardly by a spiral spring 13 located in the housing in operative relation to the end of the coupler shank. Draft links 14 are connected to the coupling shank by a draft link key 15, extending through slots 16 in opposite sides of the housing 12, and the opposite ends of the draft links are secured to the rear end of a longitudinally movable hollow compression member 17 by a key 18 extending through a key slot 19 formed in the end of the compression member. The forward end of the compression member, when in its forward position, engages the rear end of a hollow strut 20 and is slidably received in a channel 21 formed by an angular channel-shaped flange 22, see Figs. 1 and 4, extending rearwardly from the strut. The forward end of the strut engages the rear follower 23 of a draft gear 24 of any desired type which is positioned in the draft gear housing 25. The rearward movement of the rear draft gear follower 23 is limited by engagement with the stop shoulders 26 formed at the associated end of the housing 25. Similar shoulders 27 are provided at the opposite end of the housing for limiting the movement of the follower 28 at the opposite end of the draft gear which is adapted to receive strains transmitted to it through the car buffer 29. A spiral buffer spring 30 is interposed between the buffer and the associated draft gear follower 28.

Suitable mechanism is employed for permitting the coupler 10 to be shifted to coupling position somewhat in advance of the buffer and for retracting the coupler to normal operating position after the coupling operation. As illustrated, this mechanism includes a coupler shifting mechanism adapted to be operated by air pressure which can be conveniently obtained from the train air line. A cylinder 31 has a piston 32 connected by a rod 33 to a flange 34 extending downwardly from the longitudinally movable compression member 17. A passage 35 in the cylinder casting connects the cylinder with an air hose connection 36. Associated with the coupler operating cylinder 31 is a cylinder 37 having a piston 38 connected by rod 39, see Figs. 1 and 4, to the bottom of a sliding lock-plate 40 which is adapted to be raised into position between the adjacent ends of the compression member 17 and the strut 20 when the member 17 is in coupler retracting position. Obviously, the arrangement is such that the lock can be operated only when the coupler and compression member are in retracted positions. Spiral springs 41 are positioned between flanges 42 extending outwardly on each side of the lock and similar flanges 43 which are formed on the strut 20, see Fig. 4, for pressing the lock-plate toward unlocked position. An air passage 44 in the cylinder casting leads from the air hose connection 36 to the cylinder 37.

The cylinder casting is mounted for sliding movement on the car sills 45 and the front edge of the casting is engaged by a lug 46 formed on the bottom of the compression strut 20 for properly positioning the casting and also providing a backing when the cylinder 31 is operated to retract the coupler.

It will be apparent that when a car is uncoupled and no air pressure is provided for the air cylinders, the coupler spring 13 will move the coupler 10 and associated mechanism into forward coupling position wherein in the coupler itself is somewhat in advance of the face of the buffer and the mechanism will be in the position illustrated in Fig. 1. Under such circumstances, it will also be apparent that the coupling operation can be performed without materially jarring or striking the car buffer and, hence, without jarring the car body. After the coupling operation has been completed and the train air line is connected to the air connection 36 of the air cylinders, the coupler shifting piston 32 will be shifted to the rear to the position illustrated in Fig. 6, thus shifting the longitudinally movable compression member 17 to the rear and retracting the coupler into normal operating position. When the compression member 17 has been moved away from the end of the lock-plate 40 the associated piston 38 will be raised and the lock 40 moved into position between the strut 20 and

the compression member 17, as illustrated in Fig. 6, and the parts will be maintained in this position until the car is again uncoupled.

It will be apparent that the present construction provides an arrangement wherein the draft gear absorbs the shocks and strains of both the draft and the buffer mechanisms. Any jars or sudden strains to which the draft equipment may be subjected in operation are transmitted directly to one end of the draft gear 24 in the usual manner and, in the same way, buffing strains are transmitted to the other end of the draft gear from the buffer 29. In this manner the draft gear is used to absorb sudden strains and shocks from both the buffer and the draft mechanism and the positions of the follower at each end of the draft gear are determined by shoulders or flanges connected directly to the car frame.

Although I have described what I now consider to be the preferred embodiment of this invention in specific detail, various changes, additions, substitutions and omissions can be made therein without departing from the spirit of this invention or the scope of the appended claims.

What I claim as new and desire to secure by Letters Patent is:

1. The combination in a railroad car of a longitudinally shiftable coupler adapted to be positioned in advance of its normal operating position to facilitate coupling, means for yieldingly holding said coupler in advanced coupling position, a movable member connected to said coupler, a piston and cylinder for shifting said member so as to retract said coupler to operating position, a lock for holding said member in coupler retracting position and a piston and cylinder for operating said lock automatically upon retraction of said member.

2. The combination in a railroad car of a draft gear, a longitudinally shiftable coupler adapted to be positioned in advance of its normal operating position to facilitate coupling, a movable compression member, a strut for transmitting strains from said member to said draft gear, draft links connecting said member with said coupler, means for yieldingly holding said coupler in advanced position, an air operated piston associated with said member for shifting said member so as to retract said coupler to normal operating position, a lock-plate adapted to be inserted between said strut and said member when said member is in retracted position and an air operated piston for moving said lock-plate.

3. The combination in a railroad car, of a longitudinally shiftable coupler adapted to be positioned in advance of its normal operating position to facilitate coupling, means for yieldingly holding said coupler in advanced coupling position, a movable member

connected to said coupler, pressure actuated means for shifting said member so as to retract said coupler to operating position, and pressure actuated locking means for holding said member in coupler retracted operating position.

4. The combination in a railroad car, of a longitudinally shiftable coupler adapted to be positioned in advance of its normal operating position to facilitate coupling, means for yieldingly holding said coupler in advanced coupling position, a movable member connected to said coupler, a piston and cylinder for shifting said member so as to retract said coupler to operating position, and pressure actuated locking means for holding said member in coupler retracted position in response to the retraction of said member to retracted operating position.
5. The combination in a railroad car, of a longitudinally shiftable coupler adapted to be positioned in advance of its normal operating position to facilitate coupling, means for yieldingly holding said coupler in advanced coupling position, a movable member connected to said coupler, pressure actuated means for shifting said member so as to retract said coupler to operating position, a lock for holding said member in coupler retracting position, and a piston and cylinder for operating said lock automatically upon retraction of said member.

In testimony whereof, I have hereunto subscribed my name this 25th day of July, 1927.

ANDREW CHRISTIANSON.
